F. W. CURRIER

PLATE GLASS SETTING

Filed March 21, 1921

Inventor
FREDERICK W. CURRIER

By *Paul Reed*
His Attorneys

UNITED STATES PATENT OFFICE.

FREDERICK W. CURRIER, OF MINNEAPOLIS, MINNESOTA.

PLATE-GLASS SETTING.

Application filed March 21, 1921. Serial No. 454,101.

To all whom it may concern:

Be it known that I, FREDERICK W. CURRIER, a citizen of the United States, resident of Minneapolis, county of Hennepin, State 5 of Minnesota, have invented certain new and useful Improvements in Plate-Glass Settings, of which the following is a specification.

The object of my invention is to provide a 10 setting embodying means for concealing screw heads and the rough, unfinished part of the setting, so that the outside appearance will be neat and ornamental.

A further object is to provide a setting 15 embodying such ornamental and concealing means which is also readily removable to allow access to the screws or other fastening devices of the setting.

Other objects of the invention will appear 20 from the following detailed description.

The invention consists generally in various constructions and combinations, all as hereinafter described and particularly pointed out in the claims.

25 In the accompanying drawings forming part of this specification,

Figure 1 is an outside view of a portion of a glass setting embodying my invention,

30 Figure 2 is a similar view with a portion of the ornamental rail or molding removed,

Figure 3 is a transverse sectional view through the setting and a portion of the window frame, showing the manner of mounting the setting thereon,

35 Figure 4 is a perspective view of a portion of the removable section of the ornamental molding or rail.

In the drawing, 2 represents a window sill 40 and 3 a stop seated on the sill and 4 a metal rail having one longitudinal edge seated on the stop 3 and secured thereto at 5. A recess 6, preferably dove-tailed in form, is formed in the rail 4 and adapted to receive a block 7 of suitable material, such as lead or fiber,

45 this block being adapted to bear on the inner face of the glass plate 8. The lower portion 9 of the rail 4 extends in under the plate and has a longitudinal edge 10 that is seated on a plate 11 which rests upon the top 50 of the sill 2. Blocks 12 of suitable material are arranged in apertures in the lower portion 9 of the rail and rest upon the sill 2 and upon these blocks the lower edge of the plate glass is seated.

55 A rail or molding 13 is provided, having an upper portion 14 adapted to bear on the

outer face of the glass and a rib portion 15, terminating in an inwardly projecting flange 16. Brackets 17 are formed to fit the inner side of the rail 13 and bear at their upper ends on the flange 14, the lower portion of said brackets forming legs 18 terminating in horizontal, outwardly projecting foot portions 19. These brackets are of suitable width, from two to three inches, and are arranged a suitable distance apart in the rails 13 and are secured in the setting by suitable means, such as screws 20. The rail 13 and the brackets may be assembled at the factory or at the work, as may be desired, 60 the space between the brackets providing for a suitable drainage and effecting a saving in metal over a construction where the brackets would be continuous for the length of the setting. The rail or molding 13 forms a 65 finish or ornament for the upper portion of the setting and to complete the work, I provide a lower rail or section 21 having a foot portion 22 adapted to be slipped under the portions 19 of the brackets and an upper 70 or flanged edge 23 that is inserted into the space between the bracket and the adjacent edge of the rail 13. When the lower rail section 21 is inserted, the joint between it and the upper section will be entirely concealed 75 and the two sections will have the appearance of one continuous rail, presenting a neat, ornamental appearance to the exposed portion of the setting.

Drain openings 24 are provided in the 80 lower portion of the rail 21 and whenever desired, this rail may be removed by the insertion of a suitable tool into one of these openings. When this has been done, the screws 20 or other securing means for the 85 brackets will be exposed. The rails and brackets may be made of any suitable material, preferably metal of suitable thickness, and the surface of the ornamental rail or molding may be finished in any preferred 90 manner.

I claim as my invention:

1. A separable longitudinally extending glass setting comprising an upper moulding section, means for holding it to the glass, 105 and a lower moulding section normally entirely on the same side of the glass forming a continuation of said first section, said sections normally concealing the holding means.

2. A plate glass setting including upper 110 and lower rail sections and means for secur-

ing one section to the sill of a window, the other section being movable relative to said one section and having one edge normally interposed between the glass and said securing means, said sections normally concealing the securing means, and one section forming with the other section a continuous finish moulding.

3. In a window structure a plate glass setting including a rail composed of separable upper and lower sections entirely on the same side of the glass, means for mounting said upper section against the glass, the lower section having one edge seated on the sill and the other edge inserted between the glass and said upper section and forming a continuation of said upper section.

4. In a window structure a plate glass setting including an upper rail section, brackets mounted on said structure at intervals and having depending legs provided with means for securing them to the window stop, and a lower rail section seated on the sill and having an upper edge inserted between said legs and the lower edge of said upper section said sections concealing said brackets and legs and said securing means.

5. A plate glass setting comprising an upper rail section having an upper portion to be seated against the glass and a lower ribbed portion terminating in an inwardly projecting flange, a lower rail section adapted to be seated on the sill and having an upper edge normally inserted in the rear of said flange normally concealed thereby, and means for securing said upper section in place and normally concealed by said sections, said lower section being separable from said upper section and movable into normal position while said upper section is disposed in operative association with the glass.

6. A separable glass setting including a moulding section, means for holding said section to the glass, and a second moulding section normally entirely on the same side of the glass adapted to form a transverse continuation of said first section, said moulding sections normally extending over and concealing the holding means.

7. A glass setting comprising an inner rail having means for bearing on the inner

face of the glass, brackets normally mounted on the outer side of the glass and means for securing them to a window sill, and an ornamental rail composed of separable sections normally mounted on the same side of the glass to conceal said brackets.

8. The combination, with a sill and stop and a glass plate and blocks supporting said plate on said sill, of an inner rail having means to bear on the inner face of the glass, brackets arranged on the outer side of the glass and each having a securing means, and an ornamental rail entirely on the outside of the glass in separable sections one above the other for concealing said brackets.

9. A glass setting comprising brackets each having a foot and an upstanding overhanging portion, means for holding the brackets in place and a moulding section having a portion normally resting under the feet of the brackets and engageable therewith, and a second section having an upwardly extending portion passing over the brackets and thence downwardly between the brackets and the glass, and a portion resting under the overhanging portions of the brackets to conceal the lower parts of the brackets.

10. A glass setting comprising brackets each having an upstanding overhanging portion and an upper end to hold the glass and a molding section having a portion normally resting between the upper end of the brackets and the glass and a downwardly extending portion extending around the overhanging portions of the bracket for concealing the upper parts of the brackets.

11. A glass setting comprising brackets each having a foot and an upstanding portion, means for holding the brackets in place, a lower moulding section having a portion normally resting under the feet of the brackets, an upwardly extending portion to conceal the lower parts of the brackets, and an upper moulding section having a portion normally resting between the upper ends of the brackets and the glass and extending downwardly over the brackets to conceal their upper portions.

In witness whereof, I have hereunto set my hand this 17th day of March, 1921.

FREDERICK W. CURRIER.
